BURIAL CASKET

William I. Davis, St. Louis, Mo.

Application March 11, 1940, Serial No. 323,441

2 Claims. (Cl. 27—2)

The invention relates to a burial casket and more especially to a moistureproof casket.

The primary object of the invention is the provision of a casket of this character wherein the body has its cover hermetically sealed in a manner to exclude the entrance of moisture to the interior and within the casket vapor from the corpse when confined therein will have exit so as to eliminate moisture from within the said casket, resulting in a moistureproof casket.

Another object of the invention is the provision of a casket of this character wherein the body and cover are made from sheet metal, being streamlined, and interiorly of such casket is arranged a condenser so that when the casket is sealed bacteria action set up resulting in a form of vapor given off from the corpse will be trapped or collected and dispersed from such casket and in this manner maintaining a dry preservation of the corpse within the casket.

A further object of the invention is the provision of a casket of this character wherein surface or underground burial may be had and in any event with respect to the character of burial the casket will be moistureproof and will emit or deliver moisture from within the said casket so that the corpse will be preserved in a dry state, the manner of discharging the moisture thrown off from a corpse when hermetically sealed within a casket is novel and the structure for accomplishing this is unique.

A still further object of the invention is the provision of a casket of this character, which is simple in construction, thoroughly reliable and efficient in its operation for the purposes stated, susceptible of long life, neat in appearance, and inexpensive to manufacture.

With these and other objects in view, the invention consists in the features of construction, combination and arrangement of parts as will be hereinafter more fully described in detail, illustrated in the accompanying drawings, which disclose the preferred and modified forms of embodiment of the invention and pointed out in the claims hereunto appended.

In the accompanying drawings:

Figure 1 is a vertical longitudinal sectional view through a casket constructed in accordance with the invention and adapted for underground burial.

Figure 2 is a bottom plan view of the cover of the casket removed from the body of the same.

Figure 3 is a sectional view taken on the line 3—3 of Figure 1 looking in the direction of the arrows.

Figure 4 is a sectional view taken on the line 4—4 of Figure 1 looking in the direction of the arrows.

Figure 5 is a vertical longitudinal sectional view, partly in elevation, illustrating a modified form of casket adapted for surface or mausoleum burial.

Figure 6 is a bottom plan view of the interior setup for the casket as shown in Figure 5, the drain devices being removed therefrom.

Figure 7 is a sectional view on the line 7—7 of Figure 6 and illustrating the drain devices in connected relation with the spouts.

Similar reference characters indicate corresponding parts throughout the several views in the drawings.

Referring to the drawings in detail, particularly to the form of casket for underground burial depicted in Figures 1 to 4, inclusive, the casket in its completed setup comprises a body 10 and cover or lid 11, respectively, preferably made from sheet metal, and such are of elongated, streamlined formation. The side walls 12 and the end walls 13 of this body 10 have the upper portions thereof about the top opening of the body instruck to form an inwardly offset, unbroken, ledge-forming rim 14 fashioned with a downwardly disposed counterseat 15, the latter accommodating therein a right angularly disposed, subjacent portion 15a formed on the inner end of a horizontally and inwardly disposed flange 16 defining the lower end of the cover 11. The flange 16 and portion 15a are disposed in substantially appressed relation with the rim 14 and walls defining the countersink 15 and are hermetically sealed thereto after the placing of a corpse within the said body for burial purposes, either underground or above the surface.

The body 10 interiorly thereof is decoratively lined, including cushions and padding at the bottom, sides and preferably one end, as at 17 and 18, respectively, while preferably within this body 10 at the other end is a decorative head rest or pillow 19. The interior finishing of the body 10 is conventional to modern casket manufacture.

Attached to the cover or lid 11 or in any manner suspended therefrom interiorly of the body 10 when the said lid or cover is applied thereto is a condenser in the form of an upwardly curved elongated hood or dome-like section 20, being tapered from one end toward the other in conformity with the placement of the head and feet of the corpse within the body 10 so that the smaller end will overhang the feet and the wider end the head of said corpse. The hood or dome-

like section 20 has formed at opposite longer sides thereof and entirely across one end, that is, the smaller end thereof, a drain trough or gutter 21. The side stretches of the trough or gutter 21 are inclined in the direction of the wider end of the said hood or dome-like section 20 where these side stretches merge or open into downwardly convergent delivery spouts or chutes 22. These spouts or chutes 22 communicate with a combined liquid trap or catch basin and outlet device 23 equipped with a return check valve 24, spring closed and automatically opened or released so that on the opening thereof liquid within the device 23 will discharge therethrough to without the body 10.

When a corpse is placed within the casket and the cover or lid 11 is hermetically sealed upon the body 10, after the passing of several hours bacteria action takes place within the corpse. This bacteria action results in moisture or vapor being thrown off from the corpse and by the presence of the condenser interiorly of the casket suspended from its cover or lid 11 such moisture or vapor accumulates or deposits on the hood or dome-like section 20 and on condensation flows into the trough or gutter 21 thence continues to flow into the spouts or chutes 22 for delivery into the device 23 and becomes discharged therefrom on the opening of the valve 24 to the exterior of the casket. In this way the casket will be rendered dry within and the hermetically sealed lid or cover 11 as well as the normal closure of the valve 24 in the device 23 precludes the entrance of moisture from without to within the said casket, thus resulting in a moistureproof casket construction.

In Figures 5 to 7, inclusive, of the drawings there is depicted a modification of the invention wherein the casket is particularly adapted for surface or mausoleum burial. The body 25 of the casket has its cover or lid 26 hermetically sealed thereto at the joint 27 in the same manner as the joint created at 14, 15, 15a and 16 hereinbefore described, yet the principle of assembly is the same. Within the body 25 of the casket is a condenser in the form of a hood or dome-like section 28, being removable from within said body independently of the removal of the lid or cover 26. This hood or dome-like section 28 is upwardly arched with reversely sloping opposite ends 29 and throughout the opposite longer sides and crosswise of opposite ends thereof is a continuous trough or gutter 30. The side stretches and the end stretches of the same are upwardly arched and at the points 31 of these stretches intersecting with each other there is provided downwardly extending spouts or chutes 32 inserted within and communicating with the upper vertical end sections 33 of outlet devices 34 fixedly arranged within the body 10 for the

alignment of the spouts or chutes 32 therewith. The devices 34 are each provided with a laterally disposed drain section 35 extending through the adjacent side of the body so that moisture present within the body 25 having the cover or lid 26 hermetically sealed thereon will discharge laterally and exteriorly of the casket onto the floor or other support for the casket and maintain the same dry within. In other words, the moisture emitted from the corpse in vapor character will deposit on the hood or dome-like section 28 and on condensation, flow through the trough or gutter 30, the spouts or chutes 32 and the devices 34 for discharge to without the casket as heretofore explained and for the purposes set forth. It is to be understood that the various drainage parts are to be constructed of rustproof material to present smooth drainage surfaces and thus preclude clogging and the like.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and sub-combinations.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation, which are capable of extended application in various forms, and that the invention comprehends all construction within the scope of the appended claims.

What is claimed is:

1. A casket, comprising a body having a lid for closing the same, a hood-like section arranged interiorly of the body close to the lid and having all of its walls sloping downwardly, a trough carried by the inner lower ends of all the walls and adapted to receive the condensation passing from the walls, and a spout communicating with said trough and extending through the lower end of the casket for conveying the condensation from the casket.

2. A casket, comprising a body having a lid for closing the same, a hood-like section arranged interiorly of the body close to the lid and having all of its walls sloping downwardly, a trough carried by the inner lower ends of all the walls and adapted to receive the condensation passing from the walls, a spout connected to said trough and communicating with the exterior of the casket for conveying the condensation from the casket, and a relief valve for closing said spout.

WILLIAM I. DAVIS.
